erated, for example, as illustrated in Fig. 3, twelve such positions for pitches between 1 mm. and 12 mm. The inner row of said scale 34 indicates the coordinated rotational speed of the workpiece spindle 7 ranging from 60 to 15 R. P. M. and readable on the speedometer 28. The said rotational speeds conform to an approximately constant traverse or rapid return speed of the guide screw 2 over the entire setting range equivalent to a return speed of about 2 meters per minute of the workpiece support such as the grinding slide 1.

The guide or feed screw 2 is connected with the centrifugal governor 32 by a clutch for example a pin clutch 33 as shown schematically in Fig. 1 and in detail in Fig. 4. The guide screw 2 being driven by the change gear 8 rotates in a bearing 35 attached to the governor casing 42. The clutch 33 comprises a driving disc 38 which is keyed upon shaft 39 mounted in said casing 42 and is provided with a pin 37 adapted to engage a radial groove 36 in the end face of guide screw 2. A counter-shaft 41, rotatably mounted in the casing 42, has keyed upon it a smaller pinion 43 and a larger pinion 44 which engage, respectively, a larger pinion 40 keyed upon said shaft 39 and a smaller pinion 45 keyed upon an end shaft 46 which is also rotatably mounted in said casing 42, and supports the sensitive parts of the centrifugal governor 32. Shaft 46 thus rotates at higher speed than the guide screw 2 thereby increasing the sensitivity of the governor 32.

On a flange 47 secured to the cover 48 of the casing 42 are mounted two semi-circular contact or slip sheets 49, 50 which are separated between both their ends by a gap 51. A disc 52 rotating with said end shaft 46 supports upon intermediate distancing sleeves 53 three one-armed and electrically conductive swing levers 54 in triangular arrangement each lever being provided at its outer end with a contact brush 55 and a weight 56. A circular or spiral spring 57 surrounds said brushes 55 and holds the same in contact with said contact sheets 49, 50 against arising centrifugal forces. The said three swing levers 54 with brushes 55 are electrically connected over a contact ring 58 and strands 59 soldered thereto. The triangular location of the brushes 55 and the paired arrangement of the semi-circular contact sheets 49, 50 insure an electric circuit as long as the said brushes are not lifted from said contact sheets by an excessive centrifugal force.

Fig. 2 shows the regulators 25 and 27 of the variable-speed motor 5 being located in parallel conduits 60 and 61, respectively, within the circuit of the field winding 62 of the said motor. The same is switched in by the relay switch 63 for the working operation or by the relay switch 64 for the quick traverse operation, said relay switches 63, 64 being actuated by the press keys 29, 30, respectively, as described above. The relay switch 63 includes contacts 63¹, 63², 63³, 63⁴, 63⁵, 63⁶ their association being indicated by the dotted line 63a, and the relay switch 64 includes contacts 64¹, 64², 64³, 64⁴, 64⁵, 64⁶ their association being indicated by the dotted line 64a. The press key 29 operates the auxiliary contact 29¹ and 29² shown on dotted line 29a and the press key 30 the auxiliary contacts 30¹ and 30² shown on dotted line 30a. The centrifugal governor 32 and the guide screw 2 are also schematically shown in Fig. 2.

My device operates as follows:

If the press key 29 for the working operation of the machine is depressed the auxiliary contact 29¹ will be closed and the auxiliary contact 29² opened. Thereby the relay switch 63 for the working operation of the machine will be switched in and the associated contacts shown on dotted line 63a will be actuated as follows: The contact 63¹ will be opened and thereby the relay switch 64 for the rapid traverse disconnected. The contact 63² will be closed and thereby a holding current for relay 63 initiated. The contact 63³ will be opened thereby disconnecting regulator 27 for rapid-traverse from conduit 61.

Thereafter only the regulator 25 controlling the operational working speed of the motor remains switched in. The contacts 63⁴, 63⁵ and 63⁶ are closed and switch in the motor 5. When the press key 31 is depressed the current between the circuits I and II will be interrupted and the holding contact 63² and relay switch 63 will drop. If now the press key 30 for rapid traverse is depressed contact 30¹ opens, contact 30² closed and the relay switch 64 attracts and interrupts the circuit for the relay switch 63 by opening the contact 64¹. Simultaneously the contact 64² for the holding circuit of relay 64 is being closed. The contact 64³ within conduit 60 of the regulator 25 for the operational working speed will be opened and the regulator 27 for rapid-transfer will alone determine the speed of motor 5. In addition contacts 64⁴, 64⁵ and 64⁶ are also closed thereby switching in the motor 5 to turn at the higher speed for rapid return traverse which speed is set in dependence of the pitch or lead of the generated screw and is approximately constant for the entire switch range of regulator 27 being independent of the actually set working speed.

Should inadvertently the regulator 27 operated by the rotary grip 26 be set for a smaller pitch or lead than that being actually generated, then the guide screw 2 will be rotated at a speed which is higher than the approximately constant return speed whereby the centrifugal governor 32 having been adjusted to said constant return speed will become active and distance the contact brushes 55 from the contact segments 49, 50, thus momentarily stopping the driving motor 5.

Having shown and described in detail one specific embodiment of my invention to illustrate the application of the principles of my invention, it will be well understood that the same may be otherwise embodied without departing from such principles and without avoiding the scope of the appended claims.

What I claim as my invention is:

1. In a thread generating machine the improvement comprising a slidable workpiece support; a feed screw for said support mounted rotatably but axially unshiftably therein; stationary threaded means receiving said feed screw to cause an axial displacement thereof together with the workpiece support during the rotation of said screw; a workpiece spindle rotatably mounted in said support; and an adjustable change gear operatively connecting said feed screw and said spindle; said change gear adapted to vary the ratio of the rotations of the feed screw and the workpiece spindle in accordance with the pitch of the thread to be generated upon the workpiece; an electric variable speed motor driving said workpiece spindle; a first and a second regulator to vary the speed of said motor; said regulators operating alternately and independently of each other; the first regulator controlling and setting the operational or working speeds of said workpiece spindle; and the second regulator controlling the higher reverse speeds of said spindle and setting such reverse speed in such dependence from the pitch of the actually generated thread that the highest admissible return speed of the feed screw and thus of the workpiece support results, such highest admissible return speed being at least approximately constant for any pitch of generated threads and indicator means associated with the second regulator, said indicator means defining setting positions for specific return speeds of the feed screw in dependence from the pitches of threads to be generated.

2. In a thread generating machine as defined in claim 1 a centrifugal governor rotating with the feed screw and adapted to switch off the said motor if the admissible return speed of said screw is exceeded.

3. In a thread generating machine as defined in claim 1 a centrifugal governor, a transmission gear between said feed screw and said governor rotating the same at higher speed, said governor being adapted to switch off

the said motor if the admissible return speed of the screw is exceeded.

4. In a thread generating machine the improvement comprising a slidable workpiece support; a feed screw for said support mounted rotatably but axially unshiftably therein; stationary threaded means receiving said feed screw to cause an axial displacement thereof together with the workpiece support during the rotation of said screw; a workpiece spindle rotatably mounted in said support; an adjustable change gear operatively connecting said feed screw and said spindle; said change gear adapted to vary the ratio of the rotations of the feed screw and the workpiece spindle in accordance with the pitch of the thread to be generated upon the workpiece; an electric variable speed motor driving said workpiece spindle; a gearing including clutch means between said motor and said workpiece spindle driving the latter selectively at lower working speeds and higher reverse speeds, respectively; a first and a second regulator to vary the speed of said motor; said regulators operating alternately and independently of each other; the first regulator con-

trolling and setting the operational or working speeds of said workpiece spindle; the second regulator controlling the higher reverse speeds of said spindle and setting such reverse speed in such dependence from the pitch of the actually generated thread that the highest admissible return speed of the feed screw and thus of the workpiece support results, such highest admissible return speed being at least approximately constant for any pitch of generated threads; and indicator means associated with the second regulator, said indicator means defining setting positions for specific return speeds of the feed screw in dependence from the pitches of threads to be generated.
